UNITED STATES PATENT OFFICE

145,375

DESIGN FOR AN HOURGLASS UNIT

Peter Artzt, New York, N. Y.

Application February 2, 1946, Serial No. 126,173

Term of patent 3½ years

(CL. D42—7)

To all whom it may concern:

Be it known that I, Peter Artzt, a citizen of the United States, residing at New York city, in the county of New York and State of New York, have invented a new, original, and ornamental Design for an Hourglass Unit, of which the following is a specification, reference being had to the accompanying drawing, forming part thereof.

In the drawing:

Fig. 1 is a front view of an hourglass unit showing my new design;

Fig. 2 is a side view of the ball-shaped member

of the unit resting in a horizontal position; and Fig. 3 is a top perspective view of the disclosure in Fig. 2.

The essential features of my design for an hourglass unit reside in the configuration and surface ornamentation of the ball-shaped portion thereof, the support being omitted in Figs. 2 and 3 for convenience of illustration.

I claim:

The ornamental design for an hourglass unit, substantially as shown and described.

PETER ARTZT.
